Primary Examiner — Deanna L Pratt*Assistant Examiner* — Lilyana Bekic(57) **CLAIM**

The ornamental design of a hand-held device for treatment or control of medical condition, as shown and described.

DESCRIPTION

FIG. 1 is a perspective view of a hand-held device for treatment or control of medical condition showing my new design; FIG. 2 is a front view thereof; FIG. 3 is a back view thereof; FIG. 4 is a left side view thereof; FIG. 5 is a right side view thereof; FIG. 6 is a top view thereof; and, FIG. 7 is a bottom view thereof.

The broken lines in the drawings illustrate portions of the hand-held device for treatment or control of medical condition which form no part of the claimed design.
